UNITED STATES PATENT OFFICE.

JOHN A. CARSON, OF HUNTINGTON, NEW YORK.

VALVE.

1,381,795.

Specification of Letters Patent. Patented June 14, 1921.

Application filed November 15, 1919. Serial No. 338,247.

To all whom it may concern:

Be it known that I, JOHN A. CARSON, a citizen of the United States, residing at Huntington, in the county of Suffolk and State of New York, have invented new and useful Improvements in Valves, of which the following is a specification.

This invention relates to valves and is of a type, intended in one instance, to be applied to the transmission case of an automobile for ascertaining the level of oil within such case; it being of prime importance that the exact amount of oil within the case be known for the proper maintenance and upkeep of the engine. This use however, is only one of numerous uses, equally as important, to which the valve herein disclosed may be put, therefore, it is to be understood that no limitation is necessarily made to the present use.

With the above and other objects in view, the invention resides in the simplification and in the reduction in cost of manufacture of a valve of the character mentioned and which is of such construction and whose parts are so arranged that it may be easily and conveniently opened for its intended purpose and which automatically closes itself.

In the drawing:—

Figure 1 is a view illustrating the application of the valve to the crank case and the disposition of the valve plug actuating member.

Fig. 2 is a central sectional view taken on the line 2—2 of Fig. 1.

Fig. 3 is a transverse sectional view taken on the line 3—3 of Fig. 2.

At the present time, applied to the transmission case or crank case of an automobile engine, there are pet cocks, with which the level of the oil within such cases are tested or ascertained. Such cocks are found to be wholly unsuitable for this purpose, since considerable inconvenience and trouble attends their being opened and closed—requiring a person to get beneath the engine to actuate them. By the use of the particular valve herein disclosed such inconvenience and trouble may be obviated—since the valve is of such construction that it may be opened from a point at one side of the automobile by a simple outward pull—the valve automatically closing itself upon the cessation of the pull.

Referring now to the drawing, it will be

seen that the valve comprises a body 10 which is provided with an integral screw threaded extension 11. In the extension 11, extending centrally therethrough is a passage 12 which communicates with a centrally disposed opening or bore 13 in the body 10. This bore 13 is conformed to receive a tapered or cone-shape plug 14 which normally lies disposed against seat 15 formed by the wall of the bore 13.

In order that the plug 14 may be held normally against seat 15, the plug 14 is provided with a reduced threaded extension 16 at one end thereof and a spring 17 surrounds the extension 16 and is interposed between a nut 18 at the end of the extension 16 and a washer 19 which encircles the extension 16 contiguous the body 10.

In order that the plug 14 may be moved to an opened position, conveniently, from a point at one side of the automobile there is provided a pull member 20 having one end thereof attached to an apertured extension 21 on the plug 14, the other end of the member 20 being disposed in a guide member secured to the underside of the running board 23, clearly shown in Fig. 1 of the drawing. The other end of the pull member 20 is provided with a finger ring 24. The threaded end of the extension 11 is received in a threaded aperture in the crank case 25.

From the foregoing it will be manifest that there is provided a valve which is of simple construction, and which is particularly suitable to permit its being opened from a remote point, conveniently and effectually; that by pulling outwardly on the member 20 the plug 14 will be moved to a position to permit the oil to flow through the passage 12 into an established passage between the face of the plug 14 and the seat 15 of the body 10; that upon releasing the pull on member 20, the plug will automatically move back to a closed position; that by reason of the particular construction of the valve, it cannot in any way become impaired from dust, dirt, or other foreign matter, as is the case with pet-cocks and the like, since with the present valve, the oil has to pass between the plug 14 and the wall of the bore 13—a film of oil continually occurs between the plug and the wall of the bore, consequently, as the plug is permitted to move back the film of oil will be squeezed out and carries with it anything about the open end of the bore and no foreign matter.

can enter the bore while the film of oil exists between the plug and the bore.

What is claimed as new is:—

1. A valve structure as characterized comprising a body having a tapered bore therein and a screw threaded stem extending from said body and having a passage opening to said bore, a tapered plug arranged for reciprocatory movement in said bore and extending from end to end thereof, the plug being movable to permit the flow of a fluid through said passage and said bore, means at one side of the body for holding the plug in said bore and permitting the movement of the plug, and means at the opposite side of said body for moving the plug.
2. A valve structure as characterized comprising a body having a straight tapered bore therein and a screw threaded stem extending from said body and having a passage therein opening to said bore, a tapered plug arranged for reciprocatory movement in said bore and extending from end to end thereof, the plug being movable to permit the flow of a fluid through said pas-

sage and said bore, yieldable means at one side of the body for holding the plug in said bore to prevent the flow of a fluid through the passage and the bore and permitting the movement of the plug to permit the flow of a fluid as stated, and means for moving the plug from a remote point.

3. In a valve structure for use in connection with the transmission case of an engine for determining a fixed level of oil in the case, a hollow stem provided with means for connection with the said case at a point in line with the level of the oil to be determined, a body on which the stem is formed, a tapered bore opened through one end of the body, a tapered plug coacting with the bore and movable therein to permit a flow of fluid through the stem and the bore, and means for normally positioning the plug to shut off communication between the hollow stem and the said bore and allowing the reciprocation of said plug.

In testimony whereof I have affixed my signature.

JOHN A. CARSON.
